UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FILLING CLAMPING AND PARTING MECHANISM FOR LOOMS.

1,427,637.

Specification of Letters Patent. Patented Aug. 29, 1922.

Application filed May 14, 1921. Serial No. 469,599.

To all whom it may concern:

Be it known that I, ALONZO E. RHOADES, a citizen of the United States, and resident of Hopedale, county of Worcester, State of Massachusetts, have invented an Improvement in Filling Clamping and Parting Mechanism for Looms, of which the following description, in connection with the accompanying drawing, is a specification, like 10 characters on the drawing representing like parts.

This invention relates to automatic filling replenishing looms wherein the running filling is replenished prior to complete exhaustion and wherein the old or spent filling is parted between the cloth and the shuttle by a clamping and parting means mounted upon a carrier, such as the usual swinging shuttle feeler, so as to be moved bodily, 20 rearwardly and forwardly or toward and from the lay.

The object of the invention is to provide an improved, simple and effective mechanism of that type in which the filling clamping and parting device is operated when, and only when, a fresh filling carrier is transferred from the magazine or hopper to the lay.

The object of the invention is further to 30 provide a construction in which the operation of the filling clamping and parting device is secured by a striker arm movable with the filling carrier support and acting to close the filling clamping and parting device when in operative position and yieldingly movable with respect to the filling carrier support upon the occurrence of an abnormal resistance.

The object of the invention is further to 40 provide a construction in which the desired results are secured by a filling clamping and parting device having its movable member brought into closing position by an upward movement of its effective end.

45 These and other objects and features of the invention will appear more fully from the accompanying description and drawings and will be particularly pointed out in the claims.

50 The drawings illustrate the invention as embodied in a preferred form of the well known Northrop type of automatic filling replenishing loom. Such a type of loom together with filling clamping and parting mechanism of a generally similar object and

purpose is shown in the patent to Davis, 1,084,878, granted Jan. 20, 1914.

In the drawings:

Figure 1 is a transverse section of a portion of an automatic filling replenishing 60 loom with a preferred form of the present invention embodied therein.

Fig. 2 is a detail showing the position of the filling carrier support and connected parts and the filling clamping and parting 65 device when in operative position ready for transfer of a fresh filling carrier from the magazine to the lay.

Fig. 3 is a top plan view of the construction shown in Fig. 2.

The construction and operation of the automatic filling replenishing loom herein illustrated being well known and familiar to those skilled in the art and the patent to Davis above mentioned showing a construction 70 securing the same broad result as that here secured, it will be necessary to describe in detail only those features and their operation immediately concerned with the present invention.

The loom frame 1 supports the magazine or hopper 2 containing the supply of fresh filling carriers herein shown as bobbins 3. When the running filling in the shuttle 4 on the lay 5 has become substantially exhausted, 75 indication of that fact is transmitted through a well known mechanism to the rod or rock shaft 6 which is thereupon rocked to raise the arm 7 and swing the shuttle feeler 8 rearwardly and at the same 80 time to raise the dog 9 connected to the transerrer 10 into the path of a bunter 11 on the lay. If the shuttle is properly boxed, allowing the shuttle feeler to pass the end of the shuttle, then the bunter 11 striking 85 the dog 9 swings the transerrer 10 downwardly forcing a fresh filling carrier 3 from its position in the magazine down onto the lay, and in this case into the shuttle 4 there beneath, simultaneously ejecting the substantially exhausted filling carrier from 90 the lay.

When the fresh filling carrier is in the magazine 2 ready for transfer it rests against an abutment 12 and over a support 105 13 pivoted at 14 in the magazine frame so that in order to pass out from the magazine, this support 13 must be swung downwardly about its pivot. This filling carrier support 3 is a familiar device. It is rigidly con- 110

- nected to the pivot 14 which extends to the front or opposite side of the magazine and is there provided with an arm 15. This arm is provided with a notch 16 fitting over 5 a pin 17 and resting against the head 18 of the pin. This pin slides through a notched or slotted lug 19 projecting from the hopper 2 and a helical spring 20 surrounds the pin between this lug and its opposite head 21. 10 Thus the pivoted or swinging support 13 is normally held in the position illustrated but may move or swing downwardly against the tension of the spring 20 when the transfer of the fresh filling carrier takes place. 15 It is this device which is utilized to secure the operation of the filling clamping and parting device when, and only when, a fresh filling carrier is transferred from the magazine to the lay. 20 The shuttle feeler 8 acts as a carrier for the filling clamping and parting device. In the present invention this device differs from the familiar form, shown for example in the above mentioned patent to Davis, in that 25 the movable blade or member 22 pivoted at 23 to the shuttle feeler swings upwardly at its rearward or effective end to close upon the co-operating elements of the device and clamp and part the filling. The rearward 30 end of the shuttle feeler is also at its lower edge beveled or inclined upwardly as shown at 24 to insure the filling, extending from the shuttle to the fell, being guided into the field of action of the filling clamping and 35 parting device.

The general operation is a familiar one. Upon the call for filling replenishment, the shuttle feeler 8 is swung rearwardly, the movable blade 22 is swung to open position 40 and in this position the filling clamping and parting device passes over the filling extending from the substantially exhausted filling carrier to the fell. The movable blade is then swung to closing position parting and 45 clamping the filling and then when the shuttle feeler swings forwardly the clamped end of the filling is carried forwardly so as to bring the filling into the path of the usual temple thread cutter.

50 The present invention is concerned particularly with the means for closing and opening the filling clamping and parting device.

The arm 15 which is rigidly connected to 55 and swings with the filling carrier support 13 is provided with a laterally extending stud 25. An L shaped striker arm 26 is provided with a hub 27 which fits over the stud 25 and is held in place by a washer 28 and 60 a pin 29 extending transversely through the end of the stud 25. A helical spring 30 surrounds the stud 25 in the interior of the hub 27 and is secured at one end 31 to the arm 15, while the other end 32 extends out 65 through the hub and rests on top of the

arm 26 and beneath a guiding flange 33. The striker arm 26 at its rear edge is provided with a longitudinally adjustable set screw 34 abutting against the lower end of the pin 29. It will thus be seen that the 70 spring 30 holds the striker arm with the set screw 34 against the pin 29 which therefore constitutes a stop so that the striker arm moves with the filling carrier support 13. This spring is so tensioned, however, that if 75 any abnormal resistance occurs the striker arm may yield with respect to the support 13 as the support swings downwardly upon the transfer of the fresh filling carrier.

When the shuttle feeler with the filling 80 clamping and parting device is moved to operative position the parts are in position as shown in Fig. 2, and it can be seen that, as the fresh filling carrier passes out of the magazine and the support 13 and striker 85 arm 26 swing downwardly, the latter will come into contact with the forward end of the movable blade 22 and swing it into closed position thus effecting the clamping and parting of the filling. If, however, any 90 abnormal resistance occurs to the operation of these parts the striker arm 26 will yield against the tension of the spring 30 and thus prevent breakage or injury of any of the mechanism. 95

In order to secure the opening of the filling clamping and parting device when it moves rearwardly to operative position a switch cam mechanism is provided. For this purpose, a bracket arm 35 secured to the loom 100 frame extends upwardly and forwardly and at its upper forward end is provided with a stud 36 and a stop lug 37. The switch cam is in the form of an inclined flange 38 formed on the rearward end of an arm 39 pivoted on the stud 36 and normally resting by gravity on the lug 37. The movable blade 22 of the filling clamping and parting device is provided with a laterally projecting pin 40 and the parts are so arranged that when the shuttle feeler swings to forward position carrying the clamped and parted filling end, this pin rides beneath the switch cam 38 raising the arm 39 which drops back onto the lug 37 after the pin has passed forward of it to the position shown in Fig. 1. When upon the call for filling replenishment the shuttle feeler swings rearwardly, the pin 40 rides upon the forward face of the switch cam and swings the movable blade 22 to 110 open position as shown in Fig. 2. 115

There is thus provided a simple and effective means for securing the desired results in which the movable blade is actuated to clamp and part the filling when, and only 120 when, the actual transfer of a fresh filling carrier is made from the magazine to the lay.

The adjustable feature and yielding character of the striker arm is also of great ad- 125 130

vantage in assembling and operating the cutter. By this construction the parts are readily positioned so that when the movable cutter blade is actuated to close the filling 5 clamping and parting device no injurious strain is placed upon the parts after the closing position has been reached.

Having thus described my invention, what I claim as new and desire to secure by Letters Patent, is:

1. An automatic filling replenishing loom comprising a lay, a replenishing magazine for the fresh filling carriers, means for transferring a fresh filling carrier from the 15 magazine to the lay, a filling clamping and parting device movable into position to receive the running filling when the lay is in position for transfer, a filling carrier support moved by a fresh filling carrier upon its 20 transfer from the magazine to the lay, and a striker arm movable with the support and acting to close the filling clamping and parting device when in operative position and yieldingly movable with respect to the support 25 upon the occurrence of an abnormal resistance.

2. An automatic filling replenishing loom comprising a lay, a replenishing magazine for the fresh filling carriers, means for 30 transferring a fresh filling carrier from the magazine to the lay, a filling clamping and parting device movable into position to re-

ceive the running filling when the lay is in position for transfer, a filling carrier support moved by a fresh filling carrier upon 35 its transfer from the magazine to the lay, a striker arm pivoted to swing on the support, a stop limiting the downward movement of the striker arm with respect to the support, and a spring interposed between the support 40 and striker arm and acting yieldingly to hold the striker arm against the stop, the said striker arm thus moving with the support and acting to close the filling clamping and parting device when in operative position 45 but yielding against the tension of the spring with respect to the support upon the occurrence of an abnormal resistance.

3. An automatic filling replenishing loom comprising the construction defined in claim 50 1 in which the movable element of the filling clamping and parting device comprises a blade pivoted to the shuttle feeler with its rearward effective end swinging upwardly to effect the clamping and parting operation 55 and its forward end, when the filling clamping and parting device is in operative position, lying beneath the striker arm in position to be struck thereby upon transfer of a fresh filling carrier from the magazine to 60 the lay.

In testimony whereof, I have signed my name to this specification.

ALONZO E. RHOADES.
